Attorney

UNITED STATES PATENT OFFICE

FREDERICK DIETRICHSON, OF NEW ROCHELLE, NEW YORK

MASSAGE ATTACHMENT FOR SHAVING BRUSHES

Application filed August 21, 1929. Serial No. 387,481.

The invention relates to shaving brushes and has for its object the provision of means for combining a massage applicator to the handle of the brush.

5 A further object of the invention is the provision of a massage applicator for shaving brushes provided with means for protecting the brush head and holding it in compressed position when not in use to prevent 10 the brush bristles from spreading.

A further object of the invention is the provision of a massage applicator for shaving brushes that is of tubular construction, so mounted on the brush head as to enclose it 15 and adjustable on the brush head by threaded engagement with the handle, providing means to expose a portion only of the brush head and to stiffen it when the brush head is used for softening the beard before shaving.

20 A further object of the invention is the provision of a shaving brush of the construction hereinbefore described in which the exterior of the applicator is provided with corrugations for massaging operation.

25 The invention will be described in detail hereinafter and be found illustrated in the accompanying drawings, in which—

Figure 1 is a side view in elevation of the improved shaving brush and massage attachment,

Figure 2 is a longitudinal sectional view,

Figure 3 is a view similar to Figure 1 with the massage applicator in position to protect the brush body and for use in massaging: and

35 Figure 4 is an end view.

Referring to the drawings in which similar reference characters are used to designate corresponding parts throughout the several views, the handle of the improved shaving brush is designated 1, and has a reduced extension 2 in which the brush body 3 is secured. In the drawings the handle 1 and extension 2 are shown as hollow to secure lightness in weight but obviously the handle and extension may be made solid if so desired. The extension 2 is exteriorly threaded as shown at 4, and has movably mounted therein a sleeve 5 of soft, pliable material, such for instance as rubber, 6 designating an interiorly threaded bushing secured in said sleeve, and

engaging the threads 4 on the extension 2. Said bushing may be made of any suitable material such as vulcanized rubber, or fibre, vulcanite, or other rigid material such as metal. The forward end of the sleeve 5 is 55 provided with an inwardly directed flange 7 that engages the outer end of the extension 2 and by engaging the bush body 3 serves to compress the outer ends of the brush bristles to support them in compressed relation when 60 the sleeve is moved into the position shown in Figure 3. When in the position shown in Figure 3, the sleeve 5 is adapted for use as a massage applicator, and to provide an effective applicator the outer cylindrical surface 65 of the sleeve is corrugated as shown at 8, and the outer end, or the end remote from the handle is provided with radial corrugations 9 having their outer ends alined and continuous with the corrugations 8. In use, the device may be used as a shaving brush when the sleeve 5 is in the position shown in Figures 1 and 2, and as a massage applicator when in the position shown in Figure 3. Furthermore 70 it will be apparent that when it is desired to stiffen the brush body 3 the sleeve may be arranged between the extreme positions of Figures 1 and 3 to secure the stiffness desired.

Furthermore, as hereinbefore stated, the device may be arranged as shown in Figure 80 3 when the article is not in use to protect the brush body and prevent the ends from spreading.

I claim as my invention:—

1. A message attachment for shaving 85 brushes, comprising in combination with a handle having a reduced and threaded extension, a brush body secured in said extension, a sleeve of pliable material mounted on said extension, a bushing of rigid material secured in said sleeve and interiorly threaded and engaging the threads on the extension, said bushing and sleeve being adapted to be unscrewed outwardly of the handle to protect the brush body when not in use and also 90 for use as a massage applicator, and the bushing and sleeve adapted to be screwed inwardly towards the handle when the brush is in use.

2. A message attachment for shaving 100

brushes, comprising in combination with a handle having a reduced and threaded extension, a brush body secured in said extension, a sleeve of pliable material mounted on said extension, a bushing of rigid material secured in said sleeve and interiorly threaded and engaging the threads on the extension, the outer surface of the sleeve and the end thereof remote from the handle being corrugated and providing a massage applicator, said sleeve and bushing being adapted to unscrew outwardly of the handle to position it for use as a massage applicator and to protect the brush body when not in use, and to be screwed inwardly towards the handle to expose the brush body for use.

3. A massage attachment for shaving brushes, comprising in combination with a handle having a reduced and threaded extension, a brush body secured in said extension, a sleeve of pliable material mounted on said extension, an inwardly extending flange on said sleeve engaging said brush body, a bushing of rigid material secured in said sleeve and interiorly threaded and engaging the threads on the extension, the outer surface of the sleeve and the end thereof remote from the handle being corrugated and providing a massage applicator, said sleeve and bushing being adapted to unscrew outwardly of the handle to position it for use as a massage applicator and to protect the brush body when not in use, and to be screwed inwardly towards the handle to expose the brush body for use, the engagement of the flange with the brush body holding said body compact and adjustment of the sleeve on the extension relative to the end of said extension providing means to adjust the rigidity of the brush.

40 In testimony whereof I affix my signature.
FREDERICK DIETRICHSON.
